UNITED STATES PATENT OFFICE.

CLIFTON E. HERMAN, OF COLUMBUS, OHIO.

AXLE STABILIZER.

Application filed April 22, 1924. Serial No. 708,280.

To all whom it may concern:

Be it known that I, CLIFTON E. HERMAN, a citizen of the United States, residing at Columbus, in the county of Franklin and

5 State of Ohio, have invented certain new and useful Improvements in Axle Stabilizers; and I do declare the following to be a full, clear, and exact description of the invention, such as will enable others skilled in 10 the art to which it appertains, to make and use the same.

It is well known that the front axles of 15 automobiles, connected with the chassis frames thereof, by cantilever springs, have a severe oscillating motion about an axis extending longitudinally of the axle, as the springs yield upwardly and downwardly, during the operation of the machine. Furthermore, when machines of this character are heavily loaded, the springs turn 20 the axle upon the above-named axis, to quite a noticeable extent. Such turning or oscillation of the front axle, materially interferes with steering and thus makes driving 25 very tiresome, particularly on rather long trips. It is however, the object of my invention to provide novel means for stabilizing the front axle against undesirable movements, so that the previous difficulties are 30 effectively overcome.

With the foregoing in view, the invention resides in the novel subject matter herein-after described and claimed, the description being supplemented by the accompanying 35 drawing.

Figure 1 is an elevation partly in section showing the application of the invention to a recent model of a well known form of automobile.

40 Figure 2 is a plan view of the construction shown in Fig. 1.

Figure 3 is a perspective view of the lug clamped to the rear end of the spring in Figs. 1 and 2.

45 Figure 4 is a view similar to Fig. 1 but illustrating an older model.

Figure 5 is a perspective view of the lug secured at the rear end of the spring in Fig. 4.

50 In Figs. 1 and 2, the numeral 1 designates a chassis frame, to which is secured a bracket 2 having a horizontal ledge 3 upon which the rear end of a cantilever spring 4 is secured, by means of an ordinary bolt 5 and a U-bolt 6. The front end of the spring 4 is secured by a front bolt 7 and a rear U-bolt

8, upon a spring seat 9 formed on the front axle 10, all of this construction being common, with the difficulties above pointed out with regard to oscillation of the axle 10. To 60 overcome this difficulty, I provide the construction described below.

A substantially vertical spring 11 has its lower end portion disposed in front of the spring 4 and seat 9, said lower portion being 65 bent horizontally rearward as at 12 and secured against the lower side of the seat 9, by the bolt 7. Behind this bolt, the spring is preferably bent downwardly as indicated at 13, to bear against the front side of the 70 axle web. The upper end of the spring 12 is formed with an opening 14 through which the front end of a radius rod 15 passes, the rear end of this rod being pivoted at 16 to a lug 17 which may well be 75 secured to the rear end of the spring 4 by the U-bolt 6. Nuts 18 are threaded on the rod 15 to abut the front and rear sides of the spring 11 and after initially applying the spring and rod, these nuts may be adjusted to place said spring under tension in the desired direction.

In Fig. 4, 1^a designates the chassis frame having a different form of spring bracket 2^a to which the rear end of the spring 4^a is 85 secured by an ordinary bolt 5^a and a U-bolt 6^a. The front end of this spring rests on a spring seat 9^a on the front axle 10^a, and an ordinary bolt 7^a and U-bolt 8^a pass entirely 90 through the axle to secure the latter and the spring 4^a together. The lower end of the bolt 7^a is utilized to secure the rearwardly bent end 12^a of a vertical spring 11^a, against the lower side of the axle 10^a. The upper 95 end of the spring 11^a is connected in the same manner as above described, with the front end of a radius rod 15^a whose rear end is pivoted to a lug 17^a which is secured upon the bracket 2^a by the bolt 5^a.

Either form of construction shown, will 100 prevent excessive oscillation of the front axle and consequently, easier steering is effected and there is less wear upon king-bolts, bearings, etc.

As excellent results may be obtained from 105 the details disclosed, they may well be followed, but within the scope of the invention as claimed, minor changes may of course be made.

I claim:

1. In an automobile chassis having a cantilever spring secured at its front end to the

front axle and secured at its rear end to a substantially vertical spring secured to said front axle and rising therefrom, a radius rod connected at its front end with the upper end of said substantially vertical spring, and means pivotally mounting the rear end of said radius rod at the rear end of the vehicle spring.

10. 2. In an automobile chassis having a cantilever spring secured at its front end to the front axle and secured at its rear end to a spring bracket on the chassis frame; a substantially vertical spring secured to said front axle and rising therefrom, the upper end of said vertical spring having an opening, a radius rod whose front end passes through said opening, adjusting nuts threaded on said rod and engaging the front and rear sides of said vertical spring, and means pivotally mounting the rear end of said radius rod at the rear end of the vehicle spring.

25. 3. In an automobile chassis having a front cantilever spring resting at its front end upon the front axle, and means securing said axle and spring together, including a bolt passing through the spring and a part of the axle; a substantially vertical spring at the front side of said axle having a rearwardly bent lower end underlying a portion of said axle and secured against said portion by the aforesaid bolt, a radius rod having its front end connected with the upper end of said vertical spring, and means mounting the rear end of said radius rod at the rear end of the vehicle spring.

40. 4. In an automobile chassis having a front cantilever spring resting at its front end upon the front axle, and means securing said axle and spring together, including a bolt passing through the spring and a part of the axle; a substantially vertical spring at the front side of said axle having a rearwardly bent lower end underlying a portion of said axle and secured against said portion by the aforesaid bolt, the upper end of said vertical spring having an opening, a radius rod whose front end passes through said opening, adjusting nuts threaded on said rod and engaging the front and rear sides of the vertical spring, and means pivotally

mounting the rear end of said radius rod at the rear end of the vehicle spring.

5. A stabilizing attachment for the front axle of an automobile carried by a cantilever spring, said attachment comprising a substantially vertical spring adapted at its lower end to be secured to the axle, a radius rod connected with the upper end of said spring, and means for pivotally mounting the rear end of said radius rod at the rear end of the vehicle spring.

6. A stabilizing attachment for the front axle of an automobile carried by a cantilever spring, said attachment comprising a substantially vertical spring adapted at its lower end to be secured to the axle, the upper end of said spring having an opening, a radius rod whose front end passes through said opening, adjusting nuts threaded on said radius rod in engagement with the front and rear sides of the spring, and means for pivotally mounting the rear end of said radius rod at the rear end of the vehicle spring.

7. A stabilizing device for a front automobile axle carried by a cantilever spring, said device comprising a substantially vertical spring having its lower end bent rearwardly and adapted to be secured against the lower side of a part of the axle, a radius rod connected with the upper end of said spring and extending rearwardly therefrom, and means for pivotally mounting the rear end of said radius rod at the rear end of the vehicle spring.

8. A stabilizing device for a front automobile axle carried by a cantilever spring, said device comprising a substantially vertical spring having its lower end bent rearwardly and adapted to be secured against the lower side of a part of the axle, the upper end of said spring having an opening, a radius rod passing through said opening, adjusting nuts threaded on said rod at the front and rear sides of the spring, and means for pivotally mounting the rear end of said radius rod at the rear end of the vehicle spring.

In testimony whereof I have hereunto affixed my signature.

CLIFTON E. HERMAN.
